CLAIM

I claim the ornamental design for a medical gown, as shown
and described.

DESCRIPTION

FIG. 1 is a front perspective view of a medical gown showing
a first embodiment of my new design;

FIG. 2 is a rear perspective view thereof;

FIG. 3 is a rear view thereof, with the internal components
exposed;

FIG. 4 is a rear view of a person wearing the medical gown;

FIG. 5 is a side view of a person wearing the medical gown;

FIG. 6 is a front perspective view of a medical gown showing
a second embodiment of my new design;

FIG. 7 is a rear perspective view thereof;

FIG. 8 is a rear view thereof, with the internal components
exposed;

FIG. 9 is a rear view of a person wearing the medical gown;
and,

FIG. 10 is a side view of a person wearing the medical gown.
The broken lines in FIGS. 4, 5, 9 and 10 illustrate the design
as worn, and form no part of the claim.
